UNITED STATES PATENT OFFICE.

ANDREW J. BARR, OF MANSFIELD, OHIO, ASSIGNOR OF ONE-HALF TO
HERMAN E. HOMBERGER, OF MANSFIELD, OHIO.

FLUSH.

No. 809,603.

Specification of Letters Patent.

Patented Jan. 9, 1906.

Application filed February 25, 1905. Serial No. 247,291.

To all whom it may concern:

Be it known that I, ANDREW J. BARR, a citizen of the United States of America, and a resident of Mansfield, Richland county, 5 Ohio, have invented a certain new and useful Improvement in Flushers, of which the following is a specification.

My invention relates to a device used for flushing closets or other similar apparatus; 10 and the objects of my improvements are, first, to construct a valve mechanism, appliances, and reservoir that will effectually flush the bowl in a simple and efficient manner; second, to construct a valve mechanism, in 15 combination with a reservoir, in such a manner that the flushing of the bowl can be accomplished with the water in the reservoir or in case it is desirable for any purpose to permit the water to flow through the valve without 20 interruption, thereby continuously flushing the bowl. I attain these and other objects by the mechanism illustrated in the accompanying drawings, in which—

Figure 1 is a bottom view of the reservoir and valve-seat. Fig. 2 is a cross-sectional side view of the reservoir, valve, and its appliances, showing valve closed. Fig. 3 is a cross-sectional side view of the reservoir and valve with an end view of the eccentric-pin, 25 showing valve-rod connected.

Similar figures refer to similar parts throughout the several views.

Referring to the drawings, 1 represents a reservoir that can be made any size or shape 30 desired. A screw-threaded aperture 2 is provided in the upper portion and is adapted to fit the screw-threaded exterior of the projecting portion 3 of the eccentric-pin support or journal 4. A tapered pin 5 is fitted to a corresponding aperture 6 in the support 4. An 35 adjusting-screw 7 is secured to the end of the pin and is adapted to keep the pin in close contact with the bearing, so as to prevent any leakage and take up ordinary wear. A 40 portion of the pin in direct alinement with the valve-opening is cut out, leaving a portion 9, to which one end of the valve-rod 10 is pivotally attached. A lever 11 is secured to the projecting portion of the pin for the 45 purpose of turning it in its bearings. The lower end of the valve-rod is secured to the valve 13 by connecting the hook 14, formed

thereon, with the eye 15, attached to the top of the valve. When motion is imparted to the pin 6 through the medium of the lever, 55 the valve-rod is raised or lowered, closing or opening the valve. The portion 9 is formed eccentric to the radius or center of the pin. The central portion of the support, which is in direct alinement with the inlet-pipe 16, is 60 cut away, as shown in Fig. 3, reference-figure 17. This permits the water to flow freely into the reservoir, which exerts a pressure against the valve, keeping it seated until it is raised by the lever for the purpose of flushing 65 the bowl. A seat 18 is provided in the lower end of the reservoir and can be adjusted by means of a screw-threaded exterior and interior of the parts or other well-known means of adjustments. 70

Material changes or alterations of the parts may be made without departing from the principle involved in my invention.

What I claim, and desire to secure by Letters Patent, is—

1. In a flush-valve mechanism, in combination with a reservoir of a standard having an aperture formed in the center thereof in alinement with the reservoir and secured to the upper portion of said reservoir, a tapered 80 orifice formed in said standard at right angles therewith, a rotatable tapered pin fitted to said orifice having a portion made eccentric and adapted to aline with the reservoir permitting the water from the inlet-pipe to 85 flow into the reservoir, a rod hooked to the eccentric portion of the pin with the opposite end hooked to a valve located in the lower portion of the reservoir. 75

2. A flushing device composed of a reservoir, with both ends interiorly screw-threaded, a support having one end exteriorly threaded and adapted to engage with the screw-threaded top of the reservoir, an inlet-aperture formed in said standard communicating with the reservoir, a tapered orifice formed in the support transverse to said aperture, a tapered pin fitted thereto, an eccentric formed on said pin in direct alinement with the inlet-aperture of the support, a rod 95 pivotally journaled to said eccentric on one end, an outlet-bushing fitted to the lower portion of the reservoir having a valve-seat formed thereon, a valve fitted to said bush- 100

ing and connected to the opposite end of said rod, an operating-lever secured to the projecting end of the tapered pin.

3. In a flushing device, a reservoir having an inlet and outlet in alinement with each other, a support having enlarged projecting portions attached to the upper portion of the reservoir, an inlet-aperture formed therein, a tapered orifice formed transverse to and intersecting said inlet-aperture, a tapered pin fitted to said orifice having an eccentric portion, a bushing fitted to the lower portion of the reservoir with a valve-seat formed thereon, a rod pivotally connected to said valve and tapered pin, a lever secured to said pin providing a means of opening the valve when movement is imparted to the pin.

4. A flushing-valve mechanism comprising a reservoir and support, a tapered pin having an eccentric portion formed thereon fitted to the support, a bushing secured to the lower portion of the reservoir, a valve, a rod adapted to pivotally connect said valve and ta-

pered pin, an operating-lever attached to said pin substantially as described and for 25 the purpose set forth.

5. In a flush for closets, comprising a reservoir with a support attached to the upper portion, said support having an aperture communicating with the reservoir, a tapered 30 orifice formed in said support intersecting with said aperture, a tapered pin having an eccentric portion fitted to said orifice, a bushing adapted to form a valve-seat secured to the lower portion of the reservoir, a valve 35 adapted to contact with said valve-seat, a rod pivotally connecting said valve and tapered pin, a lever secured to the projecting end of the pin as described and set forth.

Signed at Mansfield, Ohio, this 20th day of 40 February, 1905.

ANDREW J. BARR.
